ADAM LUNGEN, OF NEW YORK, N. Y., ASSIGNOR TO EDWARDS & CO., OF NEW YORK,
N. Y., A CORPORATION OF NEW YORK.

ANNUNCIATOR.

1,114,275.

Specification of Letters Patent.

Patented Oct. 20, 1914.

Application filed December 19, 1911. Serial No. 666,695.

To all whom it may concern:

Be it known that I, ADAM LUNGEN, a citizen of the United States, residing at New York, county and State of New York, have 5 invented certain new and useful Improvements in Annunciators, of which the following is a full, clear, and exact description.

The invention which forms the subject matter of this application relates to annunciators, the principal object of which consists in making an annunciator having a minimum number of parts. This I accomplish by striking up the keeper, the support for the armature support and the means for 15 limiting the gravity element, which can be punched from sheet metal in a minimum number of operations.

A further object consists in so constructing the parts that the same will occupy the 20 minimum amount of space and without interfering one with another when a plurality are used together.

Another object consists in producing an annunciator possessing, in addition to the 25 above enumerated advantage, the quality of simplicity and cheapness of manufacture.

In the drawings Figure 1 is a rear elevation of four annunciators, showing how they are grouped in sets. This figure also 30 serves as an assembly view of an individual annunciator. Fig. 2 is a rear view of the device shown partly in section. Fig. 3 is a side elevation. Fig. 4 is a front view showing the indicating arrow in front of the 35 panel and the annunciator proper in dotted lines behind the panel. Fig. 5 is a detail view of the frame and keeper showing the part which is struck up from one piece by the die.

40 Referring to the drawing in which like characters represent like parts in the different views: 10 designates a support for the keeper 16. It is to be understood that wherever the word "keeper" is used, whether in 45 the descriptive part of the specification or in the claims, I refer to that part of the struck up metal to which the electro-magnet is secured or, as in this case, suspended. This is preferably made of stamped sheet 50 iron. This support at the upper portion is provided with a tongue 11 and a groove 12. The tongue registers with the adjoining element and serves to maintain the parts in proper alinement.

55 The frame is perforated at 13 for the re-

ception of a screw or other securing means 14. This screw 14 holds the frame and keeper to the panel 15. The keeper is bent substantially at right angles to the portion 10. The keeper 16 has projecting downwardly from it two wings 17 and 18. These wings are so placed that they are slightly spaced from the support 15. The purpose of this space will be hereinafter set forth. The wing 18 has bent at right angles to it 60 two lugs 19 and 20. These lugs are perforated and a pintle 21 extends therethrough. This pintle has fastened on one end thereof the indicating arrow 22, and on the other a gravity drop 23. The lug 19 65 has extending from it two ears 24 and 25. These ears serve to limit the extreme positions of the gravity drop. The drop has a cut out portion 26 whose bottom contacts with the ear 25 and prevents further rotary 70 movement of the drop in one direction (see A, Fig. 1), and a shoulder 27 on the opposite side serves to limit its extreme movement in the opposite direction. The other wing 17 has bent at right angles to it the 75 lugs 28 and 29. The lugs are perforated and support the pintle 30 which carries the armature 31. The armature is preferably stamped out of sheet metal and is provided with two upwardly extending arms 32. 80 See Figs. 1 and 2. These arms are perforated and through these perforations passes the pintle 30 previously mentioned. One or both of these arms also serve to limit the movement of the armature in its movement 85 from the magnet, the same coming in contact with the wing 17 and thus preventing further movement of the armature about the pintle 30. One of the arms 32 is extended upwardly and carries at its upper end an 90 ear 33. The drop 23 is normally held up by this ear 33 which engages the shoulder 34. A leaf spring 35 is fastened to the armature by being bent over one end thereof, as shown at 36, and curved at the other 95 end to contact with the wing 17, as shown at 37. This spring serves to normally hold the armature away from the magnet 38. The magnet is of any suitable type and is suitably fastened to the keeper 16, as by the 100 screw 39.

The operation of the device is as follows: The parts are normally as shown at A in Fig. 1. When the circuit to the magnet is closed by some means such as a push button 110

(not shown) the magnet 38 attracts the armature 31. This magnetic attraction being great enough to overcome the tension of the spring 35, causes the armature to take 5 the position shown at B, Fig. 1. Meanwhile the lug 33 attached to arm 32 of the armature has become disengaged from the shoulder 34 of the gravity drop 23. When the drop, on account of its weight and position, 10 falls it carries the arrow 22 to indicating position as shown at B, Fig. 1. When the current ceases to flow through the magnet the spring 35 forces the armature from the magnet to the position shown at A. After 15 the indication is noticed, the attendant raises the weight 40 by suitable external means not shown which engages with the part 41, of the gravity drop. The lug 33 is cammed against the curved portion of the drop and 20 because of the spring tension from spring 35 finally drops behind the shoulder 34, thus holding up the drop and maintaining the needle in vertical non-indicating position.

The design of the annunciator permits 25 placing the annunciator elements very close together. This is accomplished by the space between the walls 17 and 18 and the rear support 15, best shown in Fig. 3. This space permits the support 10 to be placed, as 30 viewed in Fig. 1, in the rear of the row of annunciators just above. This is clearly shown in Fig. 1 by dotted lines. The tongue and groove construction shown by 11 and 12, serves also to maintain the annunciators 35 rigidly upon the panel 15 with only one screw 14 as a fastening. Another feature is that the gravity drop 23, in either raised or lowered position, is so formed that it remains substantially within the bounding 40 lines of the annunciator.

It is to be understood that while I prefer the construction herein specifically illustrated and described the invention is not 45 limited thereto, but may be embodied in other forms without departure from its proper spirit and scope as defined by the appended claims.

What I claim is:—

50 1. In an annunciator, comprising in combination, a panel upon which said annunciator is supported; a keeper comprising a member projecting laterally from said panel, a member projecting rearwardly and upwardly from the aforesaid member and adapted to be secured to said panel, and wings projecting vertically and downwardly from said keeper member, an electromagnet secured at one of its ends to and located below 55 said lateral member and between the vertical wings, an armature pivoted to one of said wings, a gravity drop supported by the other wing, and means on said armature and engaging with said gravity drop to hold the latter in either raised or lowered position, said means adapted to limit the movement of the armature from the magnet.

56 with the said wing to limit the downward movement of the armature, said arm located in its normal position in the path of said shoulder to support the gravity drop but adapted to be moved out of the said path 70 when the magnet is excited to permit the gravity member to drop.

57 2. In an annunciator, comprising in combination, a panel upon which said annunciator is supported, a keeper comprising a member 75 projecting laterally from said panel, a member projecting rearwardly and upwardly from the aforesaid member and secured to said panel, and wings extending at right angles to the panel and projecting 80 vertically and downwardly from said lateral member, an electromagnet secured at one of its ends to and located below said lateral member and between the vertical wings, an armature pivoted to one of said wings, 85 a gravity drop supported by the other wing, and means on said armature and engaging with said gravity drop to hold the latter in elevated position, said means adapted to 90 limit the movement of the armature from the magnet.

95 3. In an annunciator, comprising a panel upon which said annunciator is supported, a keeper struck up from a single piece of metal and comprising a horizontal member 100 projecting laterally from said panel, a member projecting rearwardly and upwardly from the lateral member and adapted to be secured to the panel, and wings projecting 105 vertically and downwardly from the sides of said lateral member, in combination with an electromagnet secured at one of its ends in a vertical position centrally upon said lateral member and located between the vertical wings, an armature pivoted to one of said wings, a gravity drop supported by the other wing, and means on said armature and 110 engaging with said gravity drop to hold the latter in elevated position, said means adapted to limit the movement of the armature from the magnet.

115 4. In an annunciator element, an electromagnet, a panel, a keeper for the electromagnet, means for supporting the keeper upon said panel, said support and keeper being struck up from one piece of sheet metal, and comprising a member projecting laterally from said panel, wings projecting 120 downwardly from said lateral member, one of said wings adapted to support a gravity member and the other of said wings adapted to support an armature, said keeper projecting rearwardly and downwardly from 125 said means whereby the support for another element may be located on the panel in front of the keeper and electromagnet of said first mentioned element, substantially as described.

5. In an annunciator, comprising, in combination, a panel upon which said annunciator is supported, a keeper comprising a member projecting laterally from said panel, a member projecting rearwardly and upwardly from the aforesaid member and adapted to be secured to said panel, and wings extending substantially at right angles to the vertical plane of said panel and projecting vertically and downwardly from said lateral member, an electromagnet secured at one of its ends to and located below said lateral member and between the vertical wings, one of said wings provided with lugs projecting laterally therefrom, a pintle mounted in said lugs and located parallel to the plane of its supporting wing, an armature pivoted upon said pintle and provided with an upwardly projecting arm adapted to normally contact with the said wing whereby the movement of said armature is limited thereby in one direction, the other of said wings provided with lugs projecting laterally therefrom, a pintle supported by said lugs and arranged substantially parallel to the first mentioned pintle and also parallel to the plane of the last

mentioned wing, a shouldered gravity drop fixed upon said pintle and adapted to oscillate about the same as a center, one of said lugs provided with means for limiting the movement of said drop in either direction, said upwardly projecting arm of the armature normally located in the path of movement of said shoulder and allowing free movement of said shoulder and lock the gravity member against movement in the downward direction, said gravity member adapted to be released when the magnet is excited to attract the armature, and resilient means for maintaining the armature away from the core of the magnet and the upwardly projecting arm normally in the path of the shoulder on the gravity drop.

In testimony whereof I affix my signature in the presence of two subscribing witnesses.

ADAM LUNGEN.
